UNITED STATES PATENT OFFICE.

WARREN C. DYER, OF ST. LOUIS, MISSOURI.

CURLING-IRON.

SPECIFICATION forming part of Letters Patent No. 752,051, dated February 16, 1904.

Application filed June 22, 1903. Serial No. 162,547. (No model.)

To all whom it may concern:

Be it known that I, WARREN C. DYER, a citizen of the United States, residing at St. Louis, in the State of Missouri, have invented certain new and useful Improvements in Curling-Irons; and I do hereby declare the following to be a full, clear, and exact description of the invention, such as will enable others skilled in the art to which it appertains to make and use 10 the same.

This invention relates to curling-irons such as are employed for curling hair; and it has for its object to provide a construction wherein in the iron proper, which is the mandrel over 15 which the hair is curled, may be rotated to wind the hair thereon without requiring rotation of the handles.

A further object of the invention is to provide a construction wherein by bringing the 20 handles together the mandrel may be rotated in one direction and when the handles are separated the mandrel may be caused either to remain stationary or to rotate in the opposite direction. This provides for removal of the 25 mandrel from the hair either by drawing the mandrel out of the curl or by unwinding the hair from the mandrel.

In the drawings forming a portion of this 30 specification, and in which like numerals of reference indicate similar parts in the several views, Figure 1 is a side elevation showing a curling-iron embodying the present invention. Fig. 2 is a vertical section through the iron in a plane at right angles to the pivot of the 35 handles, the segmental gear being in elevation. Fig. 3 is a perspective view showing the lower portion of the mandrel with the gear-wheel thereon. Fig. 4 is a transverse section through the curling-iron in a plane just above 40 the gear-wheel, showing the upper pawl of the gear-wheel engaged with the upper ratchet on the mandrel.

Referring now to the drawings, the present 45 curling-iron comprises a frame including a laterally-broadened-central portion 5, above and below which the frame is narrowed, as shown at 6 and 7, said frame being formed integral with and at the upper end of one of the handles 8 of the instrument, the other handle, 9, 50 of the instrument being pivoted against the

side of the handle 9 at the upper end thereof and close to the frame above referred to, the upper end of the handle 9 being provided with a segmental gear 10 for a purpose to be presently explained.

55

Through the upper end of the frame is formed a perforation 11, and in the lower end of the frame is a socket 12, this perforation and socket forming the bearings in which is rotatably and slidably mounted the lower end 60 of a mandrel 13.

The outer end portion of the mandrel 13—that is, the portion which lies exteriorly of the frame—is slotted longitudinally, as shown at 14, the free end of the slot being gradually 65 broadened at 15 to facilitate introduction into the slot of the end of the lock of hair to be curled. After the end of the lock of hair is entered in the slot 14 the mandrel is rotated to wind the hair thereon, the bearings which 70 the mandrel has in the frame permitting of this rotation.

To rotate the mandrel, a gear-wheel or pinion 16 is mounted thereon and lies in the broadened portion 5 of the frame, said pinion being held against reciprocatory movement with the mandrel by the upper and lower shoulders 75 17 and 18 of the frame, which are formed by narrowing the upper and lower portions 6 and 7 of the frame above referred to.

80

Upon the mandrel above the pinion 16 are formed ratchet-teeth 19, and additional ratchet-teeth 20 are formed on the mandrel below the gear-wheel, the spacing of these groups of ratchet-teeth longitudinally of the mandrel 85 being slightly greater than the thickness of height of the pinion. Pivoted upon the upper face of the pinion is a pawl 21, which is held yieldably against the mandrel by the spring 22 in position for engagement with the ratchet-teeth 19 when the mandrel is slid downwardly 90 into the frame. Pivoted upon the under face of the pinion is a second pawl 23, disposed in the opposite direction to the pawl 21 and having a spring 24, which holds it yieldably 95 against the mandrel, so that when the mandrel is drawn upwardly to disengage the upper ratchet-teeth 19 from the upper pawl 21 the lower ratchet-teeth 20 will be raised into engagement with the lower pawl.

100

The segmental gear 10 meshes with the pinion, so that by grasping both handles 8 and 9 and moving them toward each other the segmental gear will be caused to rotate the pinion in one direction, and when the pressure is removed from the handles they will be operated in a reverse direction to reversely rotate the pinion by means of the spring 25, which is disposed between and connected to the handles. With the upper pawl engaged with the upper ratchet-teeth the pinion will be rotated to rotate the mandrel in one direction as the handles are brought together, and as the handles are moved apart by the spring 25 the pinion will rotate reversely and independently, the mandrel remaining stationary. If, however, after the mandrel has been rotated in one direction as the handles are brought toward each other the mandrel is then drawn slightly outwardly, so as to disengage the teeth 19 from the pawl 21 and engage the teeth 20 with the pawl 23, and the handles are then released and permitted to move apart by the action of the springs 25. The return movement of the pinion will serve to reversely rotate the mandrel to unwind therefrom a lock of hair that may have been previously wound thereon.

In practice modification of the specific construction shown may be made, and any suitable materials and proportions may be used for the various parts without departing from the spirit of the invention.

What is claimed is—

1. A curling-iron comprising a frame provided with a handle, a mandrel rotatably and slidably mounted in the frame, a pinion loosely mounted upon the mandrel within the frame and held against sliding movement with the mandrel, reversely-disposed pawl-and-ratchet mechanisms carried by the pinion and mandrel disposed for alternate operative engagement as the mandrel is reciprocated through the pinion, a second handle pivoted to the first handle, and a gear carried by the second handle and engaged with the pinion.

2. A curling-iron comprising a frame provided with a handle, a mandrel rotatably and slidably mounted in the frame, a pinion mounted loosely upon the mandrel within the frame and held against sliding movement with the mandrel, reversely-disposed spring-pressed pawls mounted upon the upper and lower faces respectively of the pinion, ratchet-teeth reversibly disposed upon the mandrel above and below the pinion for engagement of the corresponding pawls alternately as the mandrel is reciprocated, a second handle pivoted to the first handle, and a gear carried by the second handle and engaged with the pinion.

In testimony whereof I affix my signature in presence of two witnesses.

WARREN C. DYER.
